UNITED STATES PATENT OFFICE.

LOUIS ROCKE, OF BROOKLYN, NEW YORK.

OPENING AND CLOSING DEVICE FOR SEPARABLE FASTENERS.

Application filed September 6, 1922. Serial No. 586,406.

To all whom it may concern:

Be it known that I, Louis Rocke, a citizen of the United States, residing at Brooklyn, county of Kings, and State of New York, have invented certain new and useful Improvements in Opening and Closing Devices for Separable Fasteners, of which the following is a specification.

The principal object of this invention is 10 to improve upon a separable fastening device of the type disclosed in United States Letters Patent 1,219,881, granted to Gideon Sundback, March 20, 1917.

The specific type of separable fastener disclosed in said patent consists of a plurality of metallic fasteners mounted upon the edges of a fabric tape or stringer, having a beaded edge upon which the fasteners are clamped and a sliding cam device is provided for causing the opposed fasteners to be brought together at a proper angle of inclination to each other to cause the cooperating fasteners to readily engage the sliding cam device when it is slid longitudinally 20 along the stringers in one direction causing them to engage and be securely locked in engagement and when slid longitudinally in the opposite direction causing the fasteners to be disengaged. In order that the device 25 as described above will function properly it has been found necessary to securely lock one end of the fabric tape edges together so that they will be brought into a proper position for permitting the sliding cam device 30 to cause the fasteners to be readily locked. This locking of the ends of the tapes or stringers is accomplished in the device disclosed in the aforementioned patent by permanently fastening the ends of the tapes or 35 stringers together by means of connecting links which are secured across the space between the edges of the tapes and are securely clamped to both tapes. Although the device described above functions perfectly its 40 practical applications and uses are decidedly limited because of the necessity for permanently securing the meeting edges of the stringers together, and although this device has been on the market for a number 45 of years and numerous attempts have been made to devise an effective means for securing the ends of the stringers detachably together, such attempts have heretofore, as far as I am aware, been unsuccessful.

The principal object of this invention therefore is to provide a new and improved

detachable clasp for securing the ends of the tapes or stringers together, whereby they may be held securely in a proper position to permit the functioning of the sliding cam. 60 Another object is to provide a clasp for a device of this character which may be readily engaged or disengaged by a single movement.

Another object is to provide a detachable 65 clasp for securing the ends of the stringers together without requiring any modification of the sliding cam device.

A further object is to provide a clasp of 70 an exceedingly simple but light construction which may be manufactured at a very low cost, will require no moving parts or springs to cause it to operate, will not add any excessive weight and will be positive and secure in its locking engagement. 75

For the accomplishment of these and such further objects as will hereinafter be apparent to those skilled in the art to which this appertains, the invention consists in the construction, combination and arrangement of 80 parts herein specifically described and illustrated in the accompanying drawings, wherein is shown a preferred embodiment of the invention, but it is to be understood that changes, variations and modifications may 85 be resorted to which fall within the scope of the claims hereunto appended.

In the drawings forming a portion of this specification:

Fig. 1 is a front elevation of a separable 90 fastener showing a detachable clasp embodying my invention attached thereto, the clasp and separable fastener being shown in locked position.

Fig. 2 is a front view, showing the ends 95 of the stringers and illustrating the manner in which the end of a stringer is inserted into the sliding cam device.

Fig. 3 is a view similar to Fig. 2 showing the position of the parts of the clasp after 100 the members thereof have been brought into engagement and before the sliding cam device has been actuated to completely lock the clasp members and fasteners.

Fig. 4 is an end view on an enlarged scale 105 of the parts as seen from the lower end of Fig. 1, and

Fig. 5 is an enlarged side view of the insertible member of the detachable clasp.

As shown in the drawings, the numerals 110 10 and 11 indicate the respective tapes or stringers having the beaded edges 12 and

12^a about which the separable fastening devices 13 are securely clamped, a limiting stop 13^a being secured to the upper end of each stringer to limit the movement of the sliding cam when it is actuated to lock the fasteners, thereby preventing disengagement of the sliding cam from the stringers.

These separable fasteners are all identical in construction and a sliding cam device 14 10 constructed of sheet metal is provided with an internal Y shaped channel having a central portion 15 and side channels 16 and 17 diverging therefrom as disclosed in the aforementioned patent, the side portions of 15 the sliding cam being spaced apart as indicated at 18 (Fig. 4) to permit the passage of the tapes.

Secured to one end of the tape 10 is a male clasp member 19 bent into a U shape 20 to form a jaw portion 20 adapted to clamp over the beaded edge 12 of the tape or stringer. The lower edge of the clasp member is cut away at an angle as indicated by the numeral 21 and projecting outwardly 25 from the clasp member substantially at the meeting point of the inclined edge 21 and outer side face 22 of the clasp member is a headed stud 23 which preferably is slightly inclined to the side face 22, as clearly shown 30 in Fig. 1. Projecting laterally from the end of the member 19 are a pair of tabs 24 which act as a positive stop to limit the movement of the sliding cam device and prevent it from coming off the stringer, when 35 the fasteners are unlocked.

One end of the tape 11 is provided with a female clasp member 25 which is formed of a piece of sheet metal bent into a U shape to provide a clamping jaw portion 26 which 40 is bent into clamping engagement with the beaded edge 12^a, the lower edge of the clasp member 25 being cut away similarly to the member 19 as indicated by the numeral 21^a, and the inclined face 21^a is slotted as indicated by the numeral 27, the slot 27 terminating at the shoulder 28 situated at the meeting point of the inclined face 21^a and the outer side face 22^a to form a stop for the headed stud 23 which is adapted to engage 50 within said slot, which has its edges turned inwardly as indicated by the numeral 29 (see Fig. 4) to hold the enlarged head of stud 23 thereby preventing detachment of the clasp members by movement in a direction transversely of the tapes.

The operation of the device is as follows, assuming that the parts are in the position shown in Fig. 1 and that it is desired to unlock the stringers the sliding cam device is moved downwardly causing the separable fasteners to be spread apart by the Y shaped channel, the fasteners on the tape 10 passing through the channel 16 and the fasteners on tape 11 passing through 60 channel 17, the wedge action of the Y chan-

nel causing the fasteners to separate. When the cam device is moved to the position shown in Fig. 3 the wedge action will separate the faces 22 and 22^a and will bring the inclined faces 21 and 21^a in contact and thus bring the slot 26 into a position that will permit the tape 11 and clasp member 25 to be slid outwardly from the cam device in a longitudinal direction and out of engagement with the headed stud 23. The tabs 24 will limit the unlocking movement of the cam device 14 and the relative positions of the tabs 24, stud 23 and slot 26 are such that the cam device will be stopped at the position indicated in Fig. 3 in which 70 position the tape 11 may be freely withdrawn. The tabs 24 also prevent the sliding cam from falling off the tape 10 when the clasps 19 and 25 are entirely separated.

When it is desired to lock the clamping 85 device and fasteners together, the reverse action takes place, the tape 11 being inserted into the channel 17, as shown in Fig. 2, the headed stud 23 engaging within the slot 26. The tape 11 is pushed downwardly until 90 the headed stud 23 engages with the shoulder 28, the parts then being in the position shown in Fig. 3, and the sliding cam device is slid upwardly as shown in Fig. 1. As the cam device slides upwardly the clasp 95 members pivot around the line of meeting of the faces 21, 21^a and 22, 22^a thus exerting a wedging action between the headed stud and the inturned edges of the slots 26 securely holding the parts in position.

While I have described the fastening devices as attached to tapes or stringers, it will be evident that they may be secured directly to any type of garments such as corsets, brassières, overalls or in any other 105 manner wherein it is desired to hold two pieces of material securely together, the term stringer as used in the claims hereunto appended is not therefore used in a limited sense, but is intended to embrace 110 any tape, fabric, leather, or material to the edge of which the metallic fasteners 13 may be secured.

Having thus described my invention, what I claim as new and desire to secure by Letters Patent of the United States, is:

1: A separable fastening device of the type wherein a plurality of metallic fasteners are permanently secured upon a pair of flexible stringers and a sliding cam device, having a central channel and diverging channels extending from and communicating with said central channel, is provided for locking and unlocking said metallic fasteners, characterized by a clasp member secured to an end of each stringer, one of said clasp members being provided with a slot and the other member with a projecting stud adapted to engage said slot, said clasp members being provided with angularly in- 120 125 130 clined faces terminating adjacent said stud to provide a fulcrum about which said clasp members are pivoted to lock said stud in said slot.

5 2. A separable fastening device of the type wherein a plurality of metallic fasteners are permanently secured upon a pair of flexible stringers and a sliding cam device, having a central channel and diverging channels extending from and communicating with said central channel, is provided for locking and unlocking said metallic fasteners, characterized by a clasp member secured to an end of each stringer, 70 said clasp members being provided with interengaging detachable locking means, said clasp members being constructed and arranged to extend into said diverging channels when said cam device is in engagement with said limiting means, whereby said clasp members will be angularly inclined to one another.

25 3. A separable fastening device of the type wherein a plurality of metallic fasteners are permanently secured upon a pair of flexible stringers and a sliding cam device, having a central channel and diverging channels extending from and communicating with said central channel, is provided 80 for locking and unlocking said metallic fasteners, characterized by a clasp member secured to an end of each stringer, said clasp members being constructed and arranged to extend into said diverging channels when 85 said cam device is in engagement with said limiting means whereby said clasp members will be angularly inclined to one another, said clasp members being provided with interengaging members adapted to be detached when said clasp members are in inclined position.

40 4. A separable fastening device of the type wherein a plurality of metallic fasteners are permanently secured upon a pair of flexible stringers and a sliding cam device, having a central channel and diverging channels extending from and communicating with said central channel, is provided for locking and unlocking said metallic fasteners, characterized by a clasp member secured to an end of each stringer, 90 said clasp members being provided with interengaging members adapted to be detached when said clasp members are in inclined position, said interengaging members comprising a stud having an enlarged head secured to one clasp member, adapted to project into the adjacent diverging channel and the other clasp member being provided with a slot to engage said stud when said last named clasp member is inserted into its diverging channel.

45 5. A separable fastening device of the type wherein a plurality of metallic fasteners are permanently secured upon a pair

of flexible stringers and a sliding cam device, having a central channel and diverging channels extending from and communicating with said central channel, is provided 75 for locking and unlocking said metallic fasteners, characterized by a clasp member secured to an end of each stringer, one of said clasp members being provided with a stud having an enlarged head, and the other of said clasp members being provided with a slot to engage said stud when said clasp members are inserted into diverging channels, the edges of said slot being turned inwardly to engage said enlarged head and prevent disengagement of said stud from 80 said slot transversely thereof.

6. A separable fastening device of the type wherein a plurality of metallic fastening means are permanently secured upon a pair of flexible stringers and a sliding cam device is provided for locking or unlocking said fasteners, characterized by a clasp member secured to one end of each stringer, one of said clasp members being provided with a headed stud and the other of said members 90 being provided with a slot, the edges of which are turned inwardly to prevent disengagement of said stud by transverse movement.

7. A separable fastening device of the type wherein a plurality of metallic fastening means are permanently secured upon a pair of flexible stringers and a sliding cam device is provided for locking or unlocking said fasteners, characterized by means for 100 detachably securing the ends of said stringers in engagement, said means comprising a clasp member secured to an end of each stringer, and one of said clasp members being provided with a pair of laterally extending tabs to limit the opening movement of said sliding cam device.

8. A separable fastening device of the type wherein a plurality of metallic fastening means are permanently secured upon a pair of flexible stringers and a sliding cam device is provided for locking or unlocking said fasteners, characterized by means for 110 detachably securing the ends of said stringers in engagement, said means comprising a clasp member secured to an end of each stringer, said clasp members being provided with detachable interengaging means and means to limit the opening movement of said sliding cam device, said limiting means constructed and arranged when in engagement with said sliding cam device to hold said clasp members in a position within said cam device permitting engagement or disengagement of said interengaging means.

In testimony whereof I have affixed my signature.

LOUIS ROCKE.
